UNITED STATES PATENT OFFICE.

LOUIS A. SUEKOFF, OF CHICAGO, ILLINOIS.

SPRING CUSHION CONSTRUCTION.

1,397,021.

Specification of Letters Patent. Patented Nov. 15, 1921.

Application filed January 30, 1919. Serial No. 273,957.

To all whom it may concern:

Be it known that I, LOUIS A. SUEKOFF, a citizen of the United States, residing at Chicago, in the county of Cook and State 5 of Illinois, have invented certain new and useful Improvements in Spring Cushion Constructions, of which the following is a specification.

This invention relates to improvements in spring cushion constructions adapted for incorporation in seat and mattress structures, and it has for its object to provide a construction of this character wherein maximum economy may be effected in the amount of 10 materials employed when producing the construction.

Furthermore, the invention also contemplates the provision of a novel form and arrangement of the spring units and their 15 envelopes, whereby but a single ply of material is present between contiguous springs, thus eliminating unnecessary use of the fabric of the envelopes and at the same time providing the requisite separation of the 20 springs to prevent their contact with each other. The sound of the springs in their relative movement with respect to each other is thereby precluded, while material saving 25 in the textile fabric of the envelopes or covering for the springs is effected.

Other objects and advantages will appear as the nature of the improvements is better understood, the invention consisting substantially in the novel construction, combination 30 and arrangement of parts hereinafter fully described, illustrated in the accompanying drawings, and finally pointed out in the appended claims.

In the drawings—

40 Figure 1 is a top plan view of one form of the invention, the springs being illustrated in dotted lines, and likewise the dividing partitions or walls for separating the springs.

45 Fig. 2 is a vertical transverse sectional view on the line 2—2, Fig. 1.

Fig. 3 is a perspective view illustrating the envelop for one series of springs, the springs being omitted.

50 Referring now in detail to the accompanying drawings, the numeral 15 designates a strip of textile fabric which is folded upon itself but in such manner that the parallel portions thereof are spaced apart a sufficient

distance to accommodate the length of a 55 plurality of springs 16. The free ends of this strip are suitably connected together, as at 17, as by stitching, or any other suitable form of fastening, thereby holding the strip in such manner that the parallel portions thereof may be distended under the expansive force of the springs 16. At suitable points in the length of the parallel portions of the strip 15 is arranged a series of 60 division walls or partitions 18. These partitions 18 are of textile fabric and their ends are fastened to the parallel portions of the strip 15, as by stitching 19 or its equivalent, thereby connecting the walls 18 at spaced 65 intervals and thus forming a series of 70 pockets or cells for the reception of the springs 16. The parallel portions of the strips 15 to which the ends of the partitions 18 are connected constitute the tops and bottoms of the several units.

75 It will be understood that each of the strips 15 may be of any desired length to provide the required size to be incorporated in the particular cushion or mattress structure, and each of these strips with its connected partition walls forms a separate unit 80 which is independent of the other strips. When each of these units is formed in the manner described they are united to a plurality of connecting walls 20, which walls 20 85 are continuous in their length, one being interposed between each two of the folded strips 15, as clearly illustrated in Figs. 1 and 2. When so arranged the side edges of the parallel portions of the strips 15 are 90 connected to the upper and lower edges of the walls 20, thus completing an envelop for each of the springs with a single ply of material at each side of the envelop. The 95 springs are thereby prevented from contacting with each other, and they may move independently without such contact, and likewise without the metallic sound that emanates from the rubbing action of their coils upon each other.

100 It is to be observed that access may be readily had to each individual pocket for inserting the springs into and removing the same therefrom. This is due to the fact that while the division walls are connected at 105 their top and bottom marginal portions, the intermediate edges are not connected, and this provides for free access to the interior

of the several pockets. Thus each individual spring may be readily placed in the pocket which it is designed to occupy and remain securely therein without the employment of any fastening means whatever.

Having thus described the invention, what is claimed as new, and desired to be secured by Letters Patent, is:

- 10 1. A spring construction of the class described, comprising a plurality of unitary spring structures having pockets therein, springs arranged in the pockets of said structures, and division walls arranged between said unitary spring structures and connected to the latter to hold the structures in assembled relation.
- 20 2. A spring construction of the class described, comprising a plurality of unitary spring structures having partitions arranged transversely thereof to divide the structures into a plurality of pockets, a spring arranged in each of said pockets, and division walls arranged between said unitary structures and connected to the latter to hold the structures in assembled relation.
- 30 3. A spring construction of the class described, comprising a plurality of unitary structures each of which has its top and bottom substantially parallel, partitions arranged transversely of each of said structures and having their ends connected to the top and bottom thereof, whereby to divide the structure into a plurality of pockets, a spring arranged in each of said pockets, and division walls arranged between said unitary structures and connected to the latter to hold the structures in assembled relation.
- 40 4. A spring construction of the class described, comprising a plurality of unitary spring structures each of which has its top and bottom substantially parallel, a plurality of partitions arranged transversely of each of said structures and having their ends connected to the top and bottom thereof, whereby to divide the structure into a plurality of pockets, a spring arranged in each of said pockets, and division walls arranged between said unitary structures, the edges of said walls being connected to the edges of

the tops and bottoms of the unitary structures to hold the latter in assembled relation.

5. A spring construction of the class described, comprising a plurality of unitary spring structures each of which has its top and bottom substantially parallel, a plurality of partitions arranged transversely of each structure and having their ends connected to the top and bottom thereof, whereby to divide the structure into a plurality of pockets, a coil spring loosely mounted in each of said pockets, the springs of each structure being separated from each other by said partitions, and division walls arranged between said unitary structures and connected to the latter to hold the structures in assembled relation, said division walls also serving to separate the springs of each unitary structure from the springs of the adjacent structures.

6. A spring construction of the class described, comprising a plurality of unitary spring structures arranged in parallel relation, each of said structures having a plurality of transversely arranged partitions to divide the same into a plurality of pockets, a spring arranged in each of said pockets, and division walls arranged between the longitudinal edges of said spring structures and connected to said edges to hold the structures in assembled relation.

7. A spring construction of the class described, comprising a plurality of units each of which is formed of a strip of fabric folded upon itself and having its ends connected, a plurality of partitions arranged between the parallel portions of said strip to divide the unit into a series of pockets, a spring arranged in each of said pockets, and division walls arranged between said units and connected to the latter to hold the several units in assembled relation.

In testimony whereof I have hereunto signed my name in the presence of two subscribing witnesses.

LOUIS A. SUEKOFF.
